UNITED STATES PATENT OFFICE

HARRY A. KOENIG, OF PHILADELPHIA, PENNSYLVANIA

PRESSING-IRON SUPPORT

Application filed September 25, 1928. Serial No. 308,147.

The present invention relates to pressing machines and more particularly to a universal control for the pressing iron of such a machine.

5 Some of the objects of the present invention are to provide an improved mechanism for pressing cloth and other material in tailoring establishments, clothing manufacturing and many other industrial plants; to provide means for supporting a pressing iron in position for more effective and efficient operation; to provide means for automatically handling the weight of a pressing iron to relieve the operator from the labor of 10 controlling such weight; to provide a support for a pressing iron whereby the range of movement of such iron is materially increased and variations of the ironing stroke can take place from a minimum to a maximum; to provide an improved mechanism for applying a constant pressure to goods being pressed; to provide means for anchoring a pressing iron in one pressing position to carry out a pressing operation while allowing the operator the freedom of both hands to arrange the material being pressed; and 15 to provide other improvements as will hereinafter appear.

In the accompanying drawings, Fig. 1 represents a perspective of a pressing machine embodying one form of the present invention; Fig. 2 represents a sectional side elevation of the same; Fig. 3 represents a sectional detail of a bearing head; Fig. 4 represents a section on line 4-4 of Fig. 3; Fig. 5 represents a sectional detail of the head support; and Fig. 6 represents a detail in side elevation of a modified form of head locking means.

40 Referring to the drawings, one form of the present invention is shown as applied to a steam pressing machine consisting, as generally considered, of a frame 10 supporting a table or bed 11 and upon which is mounted a buck or pressing board 12. When the goods are placed upon the pressing board 12 and suitably arranged for the pressing operation, a sad iron 13 is brought into pressing contact with the material and since it is 45 heated in the usual manner of such irons by

a burner receiving its gas supply by way of a pipe 14 and a steam supply by way of a pipe 15, the goods are not only heated but receive the required moistening effect to prevent scorching. A handle 16 is attached to 55 the iron 13 for manipulating it and, as here shown, is disposed at a convenient operating angle toward the operator.

For supporting the iron 13 so that it has a movement not only universal in a horizontal plane but also so that it can be raised or lowered vertically, it is connected by a ball and socket joint 17 to a rod 18 which is suspended from and rigidly attached to a hanger arm 20 which, in this instance, is of generally 60 rectangular shape and arranged with its edge parallel to the table 11. The support for the arm 20 consists, in the present instance, of a head 21 provided at opposite ends respectively with slots 22 which are vertically disposed to form guide openings for the arm 20 which traverses the slots 22 in vertical edge relation, that is to say, the arm 20 for strengthening purposes has its sides in a vertical plane. In order that the arm 20 can move relative to the head 21 easily and with a minimum amount of friction, the lower portion of the head 21 carries a track 23 which supports a plurality of ball bearing rollers 24 to serve as movable bearings upon which the arm 20 rides. The track 23 is preferably 65 adjustable as shown by the set bolts 25, in order that the bearings can be maintained in contact with the arm 20, or compensate for wear. The upper portion of the head 21 is likewise provided with a track member 26 having bearing rollers 27 held in engagement with the upper edge of the arm 20 to thus not only resist any tendency of the arm to deflect 70 upward but also to provide a free easy running bearing. Adjacent one of the slots 22 there is a projecting bearing lug 28 located above the arm 20 and in position to contact therewith, while at the opposite end of the head there is a second lug 30 projecting to 75 engage the lower edge of the arm 20, these lugs forming abutments to resist any tendency of the arm 20 to distort vertically.

In order to prevent lateral play of the arm 20, angle plates 31 are adjustably mounted 80

in pairs at opposite ends of the head 21, each pair being spaced to receive the arm 20 between them and fit snugly against the sides thereof without frictional engagement.

For the purpose of supporting the head 21 for swinging movement in a horizontal plane, it is provided with a rigid bracket 32 projecting laterally therefrom and terminating in a hub member 33 which is fixed by stud bolts 34 to a vertically disposed post 35. This post 35 forms the axis of rotation for the arm 20 and head 21 and to that end has its upper end journalled in a thrust bearing formed in a cap 36 and its lower end journalled on a step bearing formed by a cap 37 fitting over a ball race 38 which is held in interfitting relation by a spring 40, the lower end of which seats in a base socket 41. The cap 36 is bolted to a boss 42 projecting from a main rock arm 43 to fit about the post 35 while a set screw 130 is threaded through said cap in co-axial relation to the post and engages a plate 131 resting on a ball race 132. On the upper end of the set screw is mounted the usual sponge cup 133, which serves as a means for adjusting the set screw. A wing nut 134 is adapted to lock the set screw in the desired adjusted position. A second boss 44 also projects from the rock arm 43 to fit about the lower portion of the post 35, the two bosses 42 and 44 serving to transmit motion of the arm 43 to the post 35 while allowing the latter to have free rotary motion. The arm 43 serves as a relatively large bell-crank pivoted at 45 to the table frame, the head operating end of which extends substantially vertically at the rear of the machine and its other end passing substantially horizontally under the table 11. The purpose of the vertical adjustment of the post 35 is to permit the iron 13 to be adjusted to effective pressing position when the usual padding on the board 12 becomes compacted during use. This takeup permits at all times effective pressing action without any lost motion.

For actuating the bell-crank 43, its horizontally arranged end is connected by links 46 which straddle a rock lever 47 and are connected thereto by a pin 48 located intermediate the fulcrum 50 of the lever 47 and its pivoted connection 51 with an actuating rod 52. This last joins a treadle 53 pivoted to a bracket 54 depending from a bracing frame 55 of the frame 10. Pivoted to the treadle 53 is a weighted latch 56 arranged to fall just beneath the front edge of the bracing frame 55 when the treadle is depressed in order to lock the head and sad iron in their pressing position. A dog 57 is pivoted to the latch 56, and in one position is ineffective, in so far as the latch 56 is concerned, but when manually turned in another position, one end swings between the latch 56 and the treadle 53 and prevents the former from falling to latching position. A foot piece 59 is pivoted

in position to engage the latch 56 and remove it from locking engagement when the pressure upon the iron is to be relieved and the supporting parts of the iron released for movement.

For relieving the pressure upon the iron and returning the bell crank 43 to inoperative position, opposite sides of the horizontal arm of the bell crank are each provided with a boss 58 forming respectively guides for rods 60 which depend from the bed 11 and terminate respectively in heads 61. Between each boss 58 and the juxtaposed head 61 is a coil spring 62 arranged under compression, and the construction is such that release of the treadle 53 allows the two relatively heavy springs 62 to rock the bell crank 43 in the opposite direction to release the iron pressure.

In operation the goods to be pressed are placed upon the buck 12 and the iron 13 is grasped by the handle 16 and brought to the desired position above the goods. This movement is merely a swinging one because the iron is normally supported above the plane of the goods by the arm 20 and the rock arm 43 under the influence of the weight balancing springs 62. Since the radius of the arm 20 is variable, due to its sliding connection with the head 21, it will be apparent that the iron can not only be moved about the post 35 as an axis but can also travel in a straight line longitudinally of the buck 12. With the iron brought to position the treadle 53 is actuated to press the iron downward upon the goods when it can be automatically held by the latch 56 dropping under the front bar of the frame 55. When the iron is so locked exerting pressing pressure upon the goods, the operator's hands are free to manipulate and arrange the goods for pressing other portions thereof. By actuating the foot piece 59 the latch 56 is released to permit the iron to be lifted and moved to a new pressing position.

In the form of the invention of Fig. 6, a toggle locking control for the treadle 53 is shown comprising a pair of levers 63 of like size and shape pivoted respectively on opposite ends of the fulcrum pin 50 and having pivotal connection at 64 with a lug 65 projecting intermediate the ends of a lever 66. This lever 66 is provided at its upper end with a cross piece 67 arranged to abut the levers 63 to limit the relative movement of the levers 63 with respect to the lever 66. The lower end of the lever 66 is pivoted between links 68 which in turn are pivoted on a pin 70 passing through a bearing ear 71. Pedal members 72 project from opposite sides of the lever in order to kick out and release the lock so that the toggle is broken. To assist the toggle structure to maintain the position locking the treadle 53 down, the upper end of one of the levers 63 is provided with a lug 73 to which a spring 74 is attached and is

stretched to a fixed part of the machine. Where it is desired to maintain the toggle broken so that the head 21 is not mechanically held down, the end of the spring 74 is transferred to a pin 75 on the opposite side of the fulcrum 50 and hence its tension acts to hold the levers 63 and 66 in open position with the treadle 53 free for manual operation.

With the spring 74 on the pin 73, the toggle levers 63 and 66 are thrown to locking position whenever the treadle 53 is pressed down and hence the iron 13 can be freely manipulated by the operator without maintaining foot pressure upon the treadle. Being thus relieved of physically holding the treadle, the operator is unhampered in handling the iron and arranging the material being pressed. At any moment the toggle lock can be released by a kick upon the member 72.

It will now be apparent that a complete unitary pressing mechanism has been devised whereby a pressing iron is supported in a manner to relieve the operator of its weight and does not have to be manually lifted in order to reach its pressing position. Also the range of movement of the iron is materially increased over anything heretofore devised and with the increased range comes a variable radius of movement which provides universal action in a horizontal plane.

While only a single form is shown in which this invention may be embodied, it is to be understood that the invention is not limited to any specific construction, but might be applied to various forms without departing from the spirit of the invention or the scope of the appended claims.

Having thus described my invention, I claim:

1. A pressing iron mechanism comprising a table, a pressing board mounted on said table, a rock arm pivoted to said table to swing in a vertical plane, a post journaled on said arm in a substantially vertical position and arranged to move axially relative to said arm, axially yielding bearing means for supporting the lower end of said post, a head fixed to said post having front and rear aligned slots, an iron supporting arm slidably through said slots, continuous roller trackways in said head for engaging opposite sides of said supporting arm, means for adjusting said trackways to take up wear, a pressing iron pivotally suspended from the free end of said supporting arm, and means for operating said rock arm.

2. A pressing iron mechanism comprising a table, a pressing board mounted on said table, a rock arm pivoted adjacent one edge of said table and swingable in a plane intersecting the table and board, spaced bosses on the portion of the arm above the table, a vertical post slidably and rotatably mounted therethrough, an axially yieldable flexible post support engaging the lower end thereof,

a cap for the upper end of said post rigidly mounted on the upper boss, means carried by the cap for longitudinally adjusting the post, a head fixed to said post, an arm slidably mounted through said head, and an iron carried by said arm.

3. A pressing iron mechanism comprising a table, a pressing board mounted on said table, a rock arm pivoted adjacent one edge of said table and swingable in a plane intersecting the table and board, spaced bosses on the portion of the arm above the table, a vertical post slidably and rotatably mounted therethrough, an axially yieldable flexible post support engaging the lower end thereof, a cap for the upper end of said post rigidly mounted on the upper boss, means carried by the cap for longitudinally adjusting the post, anti-friction means interposed between the post ends and the cap and yieldable bottom support respectively, a head fixed to said post, an arm slidably mounted through said head, and an iron carried by said arm.

Signed at Philadelphia, in the county of Philadelphia, State of Pennsylvania, this 24th day of Sept., 1928.
